The ornamental design for a display screen with animated graphical user interface, as shown and described.

DESCRIPTION

FIG. 1 is the first image in a sequence for a display screen with animated graphical user interface showing my new design; FIG. 2 is the second image thereof; FIG. 3 is the third image thereof; FIG. 4 is the fourth image thereof; FIG. 5 is the fifth image thereof; FIG. 6 is the sixth image thereof; FIG. 7 is the seventh image thereof; FIG. 8 is the eighth image thereof; FIG. 9 is the ninth image thereof; FIG. 10 is the tenth image thereof; and FIG. 11 is the eleventh image thereof; and, FIGS. 12-22 are an enlarged view of the claimed animated graphical user interface design of FIGS. 1-11, shown enlarged and in isolation for clarity purposes.

The appearance of the animated user interface sequentially transitions between the images shown in FIGS. 1-11 and FIGS. 12-22. The process or period in which one image transitions to another forms no part of the claimed design. The broken line showing of the remainder of the user interface and display screen in FIGS. 1-11 is for environmental purposes only and forms no part of the claimed design.
